US0D1021520S

(12) **United States Design Patent** (10) Patent No.: **US D1,021,520 S**
(45) Date of Patent: ** Apr. 9, 2024

(54) **HOUSING FOR A MICRO PUREE MACHINE**

(71) Applicant: **SharkNinja Operating LLC**, Needham, MA (US)

(72) Inventors: **Eric Holzer**, Needham, MA (US); **Dan Deng**, Needham, MA (US); **Dan Kestenbaum**, Needham, MA (US)

(73) Assignee: **SHARKNINJA OPERATING LLC**, Needham, MA (US)

(**) Term: **15 Years**

(21) Appl. No.: **29/837,837**

(22) Filed: **May 9, 2022**

(51) LOC (14) Cl. **31-00**

(52) U.S. Cl.

(57) **CLAIM**

The ornamental design for a housing for a micro puree machine, as shown and described.

DESCRIPTION

FIG. 1 is a top, front and right side perspective view of the housing for a micro puree machine, embodying our new design;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a top plan view thereof; and,

FIG. 7 is a bottom plan view thereof.

The broken lines in the drawings depict portions of the housing that form no part of the claimed design.

1 Claim, 6 Drawing Sheets
